Primary Examiner—Prabhakar Deshmukh(74) *Attorney, Agent, or Firm*—Pillsbury Winthrop LLP(57) **CLAIM**

The ornamental design of a container, as shown and described.

DESCRIPTION

FIG. 1 is a top perspective view of a container according to an embodiment of the present invention in which various surfaces of the container include a “hammered metal” or “stippled” effect;

FIG. 2 is a front elevation view of the container shown in FIG. 1;

FIG. 3 is a left side view of the container shown in FIG. 2;

FIG. 4 is a right side view of the container shown in FIG. 2;

FIG. 5 is a top view of the container shown in FIG. 2; and,

FIG. 6 is a bottom view of the container shown in FIG. 2.
